UNITED STATES PATENT OFFICE.

CHARLES J. VAN DEPOELE, OF CHICAGO, ILLINOIS.

CUT-OUT FOR DYNAMO-ELECTRIC MACHINES.

SPECIFICATION forming part of Letters Patent No. 323,470, dated August 4, 1885.

Application filed November 15, 1884. (No model.)

To all whom it may concern:

Be it known that I, CHARLES J. VAN DEPOELE, a citizen of the United States, residing at Chicago, in the county of Cook and State of Illinois, have invented certain new and useful Improvements in Cut-Outs for Dynamo-Electric Machines, of which the following is a specification, reference being had to the accompanying drawings.

10 The present invention relates to devices forming part of an ordinary electric lighting circuit, and operating to prevent damage to the generator in the event of the breakage of the consumption-circuit, more especially when 15 the field-magnets of the generator are supplied with current from a source not directly dependent upon or connected to the consumption-circuit.

In the accompanying drawings, Figure 1 is 20 a diagrammatic view of apparatus arranged to illustrate my invention, the generator and switch-box being represented in elevation. Fig. 2 is a theoretic diagram of the circuits and connections. Figs. 3 and 4 are views similar to Figs. 1 and 2, except that they illustrate 25 my invention as applied to a "shunt-machine," instead of to one having a compound armature.

Similar letters indicate like parts.

A represents a dynamo-electric machine 30 the armature of which is wound with two separate sets of coils, each set being represented by a commutator and pair of brushes, substantially as set forth in Letters Patent No. 297,878, granted to me April 29, 1884. B is a box containing apparatus as follows: At its lower 35 portion is an electro-magnet, C, directly above which is arranged a pivoted lever, D, the free end of which lever extends beyond the end of the magnet and projects through a slot in the 40 side of the box, as indicated at d. Above the lever D, at the upper end of the box, is an indicator, E, from the lower portion of which, or some other equally convenient point, extends an adjustable tension device, e, and spiral 45 spring e', which latter is attached to the lever D.

The indicator E is not specifically herein described or claimed, as it will form subject-matter for a separate application intended to be filed by me.

50 Between the lever D and the indicator are located a pair of contact-bars, F G, which should be in the upward path of the lever D,

The upper one is preferably fixed in a horizontal position, while the lower one, G, is pivoted so as to be capable of free upward movement. A suitable pin or stop, g, supports the lower contact-bar in any desired position between the upper bar, F, and the lever D, which latter, being wholly or partly of iron, will be held down by its magnet when the line is in 55 operation at a point below the lower contact-bar.

The consumption-circuit passes from the armature-coils, set apart for that purpose, through the commutator H, brushes h h', and 60 binding-posts J J'. From J' it passes by conductor K to and into the box B, where its coils pass around the indicator, from whence they are continued to the electro-magnet C, leaving 65 which and issuing from the box through suitable binding-post the said conductor is carried to the lamps L or other working resistances in circuit and back through binding-post J and brush h' to the armature of the 70 generator.

The end pieces of the magnet C are of iron; but they may be of diamagnetic material, and the ends of the core be continued to their circumference with either construction. When 75 the main current is passing in the coils of the magnet, the lever D, if within its magnetic field, will be attracted and firmly held in its lowest position against the poles of the said magnet.

It will thus be seen that the consumption-circuit passes through the box B, but is not broken or in any way altered by the action of the apparatus therein contained, the safety-circuit being a separate and distinct one, as follows: The remaining coils of the armature—80 those not feeding the consumption-circuit—85 are represented by a second and usually smaller commutator, upon which bear brushes M M', from which lead two circuits, one including the field-magnet coils only, and a 90 second represented by the conductors N O, which pass directly to the box B and through suitable binding-posts to the contact-bars F G, which, as stated, are so disposed that when the lever D is depressed they are separated, 95 and the branch circuit, which, when closed, forms a short circuit around the field-coils, is 100 broken.

The operation of the device is as follows:

At starting the armature is put in motion, but no current is produced, because the spring e' holds up the lever D , bringing the contacts G and F together and short-circuiting the field-magnets across the second set of commutator-brushes; but when the lever D is depressed and held down for a moment the contacts separate, opening the branch circuit, when current is immediately produced in both divisions of the armature, one portion passing to the field-coils and the other energizing the magnet C with sufficient force to hold down the lever D , which, being so held as long as the current flows uninterruptedly, stands ready when released by the demagnetization of C to be carried upward by the spring e' sufficiently far to bring the contacts F G together, and by so short-circuiting the field-magnets to instantly stop the production of current and prevent injury to the apparatus.

As shown in the annexed drawings, the safety-switch is applied to a dynamo having a second commutator and separate armature-coils intended to energize the field-magnets of the dynamo while the first commutator and the main armature-coils are used exclusively to operate the working-circuit; but I do not limit myself to this special class of generator, since the device may be equally well applied to a shunt-dynamo by connecting the safety-circuit to the main binding-posts, as shown in Figs. 3 and 4. In this case, also, as soon as the main circuit is broken the contacts will come together and short-circuit the field-magnet coils, thus stopping the production of current and saving the machine harmless.

In practice, and especially with large dynamos, I find it absolutely necessary to use the cut-out, for, in case that the main circuit opens and the magnetism of the field-magnet is maintained, the current which before the opening was quietly flowing along the line and working-circuit, will now pass around the commutator from brush to brush, and in a few seconds the armature may be permanently disabled. However, by means of the safety-switch, the very instant the main circuit breaks the field-magnet coils of the dynamo are deprived of their current, which stops the production of current in the armature-coils, thus saving the latter harmless. Let it be remembered that in case of breaking of the main

circuit of a series dynamo the current production will be stopped by the opening of the circuit, the machine being in the main circuit, which is not the case with a double-armature machine or with a shunt-wound dynamo.

I claim—

1. In a system of electric lighting, a dynamo-electric generator having an armature with two independent circuits—one the main and the other the field-circuit—and a by-pass or circuit of low resistance around the field-magnets, said by-pass being normally open while the machine is in operation, in combination with an electro-magnet in the main circuit, said magnet being adapted on the breaking of said main circuit to close the by-pass circuit, thereby diverting the current from the field-magnets in order to stop the production of current in the armature-coils on the breakage or interruption of the main circuit, as described and set forth.

2. In a system of electric lighting in which the field-circuit of the dynamo or generator is supplied by an independent current from its armature or by a shunt from the same, an electro-magnet in the main circuit operating a short-circuiting device whenever the main circuit is interrupted or broken, said short-circuiting device shunting through a low resistance the current supplied to the field-magnets in order to deprive the latter of their magnetism, and thus to stop the production of current in the machine.

3. In a system of electric lighting wherein the field-magnets of the dynamo are excited by a derivation from the main current, an automatic circuit closer, and means, substantially as described, for holding down, as long as the working-circuit is closed, a contact-bar putting the field-coils of the dynamo in operative condition, and for short-circuiting the field-circuit whenever the main circuit is broken or interrupted, for the purpose set forth.

In testimony whereof I affix my signature in presence of two witnesses.

CHARLES J. VAN DEPOELE.
